(57) **CLAIM**

The ornamental design for a baby lounger as shown and described.

DESCRIPTION

FIG. 1 is a front, top right perspective view thereof; FIG. 2 is a back, bottom left perspective view thereof; FIG. 3 is a front view thereof; FIG. 4 is a back view thereof; FIG. 5 is a left-side view thereof; FIG. 6 is a right-side view thereof; FIG. 7 is a top view thereof; and, FIG. 8 is a bottom view thereof.

The short, even length dash-dot broken lines shown in FIGS. 1-6 are used to illustrate portions of the baby lounger that form no part of the claimed design.

The long, even length dash-dot lines shown in FIGS. 1, 2, 7, and 8 illustrate claimed stitching of the baby lounger.

1 Claim, 8 Drawing Sheets
